UNITED STATES PATENT OFFICE.

REMER T. NOLAN, OF CARROLLTON, GEORGIA, ASSIGNOR OF ONE-HALF TO HIRAM N. SPENCE, OF CARROLLTON, GEORGIA.

QUILTING DEVICE.

1,244,361.

Specification of Letters Patent.

Patented Oct. 23, 1917.

Application filed September 22, 1916. Serial No. 121,636.

To all whom it may concern:

Be it known that I, REMER T. NOLAN, a citizen of the United States, residing at Carrollton, in the county of Carroll and State of Georgia, have invented new and useful Improvements in Quilting Devices, of which the following is a specification.

This invention relates to a quilting device which may be employed to support a quilt in such a manner that the same may be quickly and conveniently stitched either by hand or with a machine.

The primary object of the invention is to provide a quilting device of this character in which a frame for holding a portion of a quilt to be stitched in an extended position is carried by a trolley mounted to travel upon a track suspended from a suitable support in an inclined position, so that as the trolley moves by gravity along the inclined track the extended portion of the quilt is passed in front of an operator seated at one end of the frame or beneath a needle on a sewing machine thus enabling the quilt to be quickly and easily stitched throughout its length in either manner found desirable.

Another object of the invention is to provide the quilting device with a trolley which is so constructed that it is both foldable and extensible thus enabling the trolley to be used in connection with quilts which vary in size and to occupy very little space when not in use.

A further object of the invention is to provide the quilting device with a quilt carrying frame which may be easily and quickly connected with or disconnected from the trolley and is so constructed that the quilt carried thereby may be supported upon the frame in such a manner that it may be readily passed beneath the needle and over the feeding mechanism of a sewing machine when it is desired to stitch the quilt in this manner and the position of the quilt changed upon the quilt carrying frame without disconnecting the frame from the trolley.

With these and other objects in view, the invention resides in the novel combination and arrangement of parts, which will be hereinafter described and particularly pointed out in the claims.

The preferred embodiment of the invention has been illustrated in the accompany-

ing drawings, although no restriction is necessarily made to the precise details of construction therein shown, as changes, alterations, and modifications, within the scope of the claims may be resorted to when desired. 60

Like characters of reference denote corresponding parts throughout the several views in the drawings, in which:

Fig. 1 is a view in elevation of the improved quilting device showing the same connected with a suitable support and in position to pass a quilt arranged upon the quilt carrying frame beneath the needle or a sewing machine for stitching the quilt.

Fig. 2 is a vertical transverse section on the line 2—2 of Fig. 1.

Fig. 3 is a plan view of the quilt holding frame.

Fig. 4 is a view in elevation of a portion of the inclined track, the trolley which is mounted to travel thereon being shown folded.

Referring now to the drawings in detail, the numeral 1 designates a support for the improved quilting device and which in this instance has been shown as the ceiling of a room, said ceiling having fixed thereto spaced brackets 2 and 3. Slotted plates 4 are slidably mounted upon the brackets 2 and 3 with each plate having formed at one end thereof a downwardly extending arm 4', the arm upon the plate on the bracket 3 being of greater length than the arm on the plate upon the bracket 2 in order that a cable 5 terminally connected with the arms 4' may be supported therebetween in an inclined position, the tension upon said cable which serves as a track being regulated through the adjustment of the plates 4 upon the brackets 2 and 3. 95

A trolley 6 is mounted to travel along the inclined cable 5 which serves as a track and is supported thereon by means of grooved wheels 7 mounted adjacent the upper ends of end bars 8 of the trolley, said end bars being held in spaced relation by slotted and crossed bars 10 having their terminals pivotally connected with the terminals of the end bars 8.

A binding screw 11 is passed through the slots in the crossed bars 10 and is provided with a nut through the adjustment of which upon the screw the end bars 8 may be moved toward each other to render the trolley adaptable for use in connection 110

with different size quilts or to be folded as shown in Fig. 4 in the drawing so that it will occupy very little room when not in use.

A quilt carrying frame 12 is swingingly connected with the trolley 6 through the medium of flexible members 13 detachably connected with rings 14 carried by the lower ends of the end bars 8, said quilt carrying frame having its side bars 15 held in spaced relation by transversely extending and slotted end bars 16, said side bars having quilt winding mechanism 17 mounted thereon, so that the position of the quilt connected with and supported by the quilt carrying frame 15 may be changed thereon as the occasion may require and a portion of the quilt held in extended position for stitching purposes.

Through the above described manner of arranging the side bars 15 and connecting the quilt carrying frame with the trolley 6, it will be seen that the quilt designated in the drawing by the numeral 18 is supported by the adjustable frame 12 in such a manner that a portion of the quilt is held in extended position between the side bars 15, so that the extended portion of the quilt may be readily passed beneath the needle on a sewing machine 20 arranged at one end of the frame and which in this instance has been shown employed for stitching the quilt 18.

When it is desired to use the improved quilting device to support a quilt during the quilting operation in such a position that it may be easily and quickly stitched either by hand or with a machine as the occasion may require, the trolley 6 is arranged in set up position upon the track 5 adjacent the bracket 2.

40 The quilt frame 12 is now swingingly connected with the rings 14 on the trolley and the quilt to be stitched arranged upon the frame 12 and connected with the winding mechanism upon the side bars 15 in such a manner that the quilt may be unwound from the winding mechanism upon one of the bars 15 and wound upon the winding mechanism upon the other bar 15 as the occasion requires.

50 If it is desired to stitch the quilt by hand, the operator may stand or sit at the right of the quilt carrying frame 12 and in such position that as the trolley 6 travels over the track 5 under the influence of gravity, the quilt upon the quilt carrying frame 12 will pass in front of the operator and may be stitched in a convenient and satisfactory manner.

When it is desired to use a machine as shown in the drawings for stitching the

quilt, the machine is arranged at one end of the frame 12 with the side bars 15 arranged upon opposite sides of the needle within the machine and as the machine is operated, the inclined track 5 will coat 65 with the feeding mechanism of the machine in causing the trolley 6 to travel toward the bracket 3 so that the portion of the quilt extending between the side bars 15 will be passed beneath the needle on the machine 70 throughout the length of the frame 12 as the trolley 6 moves over the track 5 toward the bracket 3 and upon reaching said bracket may be manually moved toward the bracket 2 and again caused to travel toward the 75 bracket 3 through the inclination of the track 5 and the feeding mechanism on the machine.

Through the above described manner of connecting the quilt carrying frame with the trolley and the trolley with the track 5, it will be seen that various designs may be formed upon the quilt by the stitching as the quilt carrying frame and trolley moves backwardly and forwardly between 85 the brackets 2 and 3.

From the foregoing description, taken in connection with the accompanying drawings, it is at once apparent that a quilting device has been provided which though extremely simple in construction and inexpensive of manufacture, is highly efficient in use for the purpose set forth.

Having thus described the invention, what is claimed as new, is:

95 1. In a quilting device, spaced and adjustable track supports, an inclined track carried by said supports, bars having rollers thereon to roll on said track, rings on said bars, a pair of crossed bars having the terminals thereof pivotally connected with the terminals of the first mentioned bars, each of said crossed bars having a slot extending longitudinally thereof for the greater portion of its length, a binding screw passing 100 through said slot and connecting said crossed bars, and a quilt carrying frame detachably connected with said rings.

2. In a quilting device, spaced brackets, a plate slidably mounted on each of said brackets and having an arm extending downwardly therefrom, said arms being of unequal length, a cable extending between and supported by said arms, an adjustable and foldable trolley to travel on said cable, 115 and an adjustable quilt holding frame detachably connected with said trolley.

In testimony whereof I affix my signature.

REMER T. NOLAN.
